UNITED STATES PATENT OFFICE.

HENRY BUSH, OF HOLGATE, OHIO.

FANNING-MILL.

SPECIFICATION forming part of Letters Patent No. 479,241, dated July 19, 1892.

Application filed December 12, 1891. Serial No. 414,814. (No model.)

To all whom it may concern:

Be it known that I, HENRY BUSH, a citizen of the United States, residing at Holgate, in the county of Henry and State of Ohio, have 5 invented a new and useful Fanning-Mill, of which the following is a specification.

This invention relates to fanning-mills or grain-separators; and it has for its object to provide a machine of this class, also known 10 as "grain-winnowers," which shall be so constructed as to effectively separate the various kinds of seeds, as well as to remove the chaff, straw, and other foreign matter to be separated from the grain, and, while accurately 15 separating, at the same time discharging each of the separations through separate passages or into separate receptacles.

With these and many other objects in view, which will readily appear as the nature of the 20 invention is fully understood, the same consists in the construction, combination, and arrangement of parts hereinafter more fully described, illustrated, and claimed.

In the accompanying drawings, Figure 1 is 25 a side elevation of a fanning-mill constructed in accordance with this invention. Fig. 2 is a vertical longitudinal sectional view of the same. Fig. 3 is a vertical transverse sectional view on the line 3 3 of Fig. 2. Fig. 4 is a 30 detail in perspective of the connected screen-carrying bars or frame-pieces. Fig. 5 is a similar view of the rectangular operating-shaft.

Referring to the accompanying drawings, 35 A A represent the side frame-pieces of the machine, forming the air-trunk therebetween and main casing. At one end thereof and also between the same is located the fan-casing B, provided with an inner discharge-opening b, communicating with the space between said side pieces, so that a blast of air from the 40 rotary fan C, mounted in said fan-casing, may be continuously blown or directed forward of the fan-casing and through said air-trunk. The fan C is mounted upon a shaft e, journaled in the bearings c', located at the end of one of said side pieces, and in the bearing-carrying frame D, located to one side of the machine at the end of the opposite side piece, 45 and mounted within said frame D is the main drive-wheel E, carried by the shaft e, journaled in bearings on said frame and operated

by the crank F, secured upon the end of said shaft. A belt f passes over said drive-wheel and said fan-shaft, and thus communicates 55 motion to the fan, while to the inner side of the drive-wheel E is secured a belt-pulley G, over which passes the crossed belt g, communicating motion to the feeding and separating mechanism, as will be presently described. 60

Directly over the fan-casing B is located the double-hopper frame H, which is detachably secured to the top of the side frame-pieces by means of the slotted angle-bracket h, secured to the side of said frame and held 65 to the top of one of said side pieces by means of the clamping-bolt h', passing through said bracket and through said side pieces.

The frame H is provided with the double hoppers I, having the ordinary inclined bottoms meeting centrally of the frame and having working thereover the hinged lid i, hinged in the opposite sides of said frame, centrally between said hoppers, so that the same may be thrown over either of the hoppers, according 70 as the grain is desired to be directed directly into the air-trunk or to first be directed upon the separating-screens. The lower outer ends of the hoppers are provided with the blocks i', having the inner vertical grooves i² 75 and the slanting grooves i³, the said vertical grooves being designed to receive the regulating or cut-off slides J, working therein, and being designed to entirely close the hoppers or to be raised and to allow the grain to be 80 fed over the edges of the respective bottoms by means of the corrugated feeding-rollers j, journaled in said grooved blocks and working under the cap or guard boards j', fitting within the slanting grooves in the inner faces 85 of said blocks, and thus causing the grain to be held to the rollers, so that the same will pass thereunder. The feeding-rollers are mounted upon shafts extending without the hopper-frame and carrying the belt-pulleys j³, 90 which are engaged by the crossed belt g from the pulley G, according as the grain is to be fed from either of said hoppers, it not being necessary to cross said belt when the innermost hopper is used to direct the grain directly into the air-trunk. The opposite shaft, 95 carrying the opposite feed-roller, is provided with a supplemental belt-pulley j³, over which the belt j⁴ passes and communicates motion 100

to the rectangular shaker-shaft K, mounted in bearings k upon the lower outer edges of the opposite sides of the hopper-frame H, and which carries upon one end thereof the belt-pulley k', over which the operating-belt j passes to communicate motion thereto, as will be readily apparent.

Within the frame H and secured to opposite sides thereof, directly beneath the hoppers I, are pivoted the vertical oscillating screen-levers L, extending above and below their pivots and carrying the screen-frame bars M, the upper opposite pair of which is pivoted to the upper ends of said levers, while the lower opposite pair of bars is pivoted upon the lower ends of the levers, so it can be readily seen that as said levers are oscillated the said frame-bars are alternately reciprocated backward and forward. The opposite levers L, adjacent to the rear end of the frame H, are extended below the lower frame-bars, as at l, and are adapted to be intermittently struck by the strike-plates l', secured upon opposite sides of the rectangular diamond-shaped or squared shaft K, at each end thereof, so that the same as said shaft revolves travel close to the inner faces of the side pieces of said frame and will intermittently strike the lower ends of said levers, so as to throw the same forward and backward, the oscillations of said levers being completed by means of said strike-plates alternately striking the downwardly-curved actuating-plates l'', secured to the under inner ends of the lower frame-bars M, and are curved below the same in the path of travel of said shaft, so that immediately after the strike-plates upon one side of the shaft have struck the lower extended ends of said levers the opposite strike-plates strike said curved plates, and thus throw the frame-bars in the opposite direction, thus causing rapid reciprocations of the same.

The frame-bars M are each provided with the inner longitudinal grooves m, that are adapted to receive the shaking-screens m', of the ordinary construction and secured within said frame-pieces by means of the locking-hooks or other suitable fastening devices m'', as illustrated in the drawings. As is usual in devices of this character, the lower screen plate or riddle, receiving the matter from the upper screen, is also provided with a forwardly-extending imperforate end m³, projecting beyond the inner end of the upper screen and adapted to carry the seed which will not pass through the perforations therein over into the air-trunk, which will complete the separations thereof, as will be described. Separations from the lower screen pass upon a conveying-pan N, located directly there beneath and carried by the lower pair of frame-bars, and said pan extends beneath said screen the length of the perforations therein. The straw or stubs or other foreign matter mixed with the grain which is fed upon the rear end of the upper screen from the rear hopper will not pass through the perforations

in said screen, but by the reciprocations thereof is discharged over the end thereof into the vibrating spout O, directly beneath said end and mounted within said hopper-frame. The inner end of said spout O, which is transversely mounted in the hopper-frame, is provided with the sliding supporting-pins o, working through the side of the hopper-frame and supporting the inner end of the spout, while the other end of the same projects through an opening o' in the opposite side of the hopper-frame and is supported by the swinging links o'', connected therewith and with said frame. The said spout O, adjacent to the inner end thereof, is further provided with an operating-stud o³, which is engaged by and works between the angle-plates P, secured to the innermost end of the upper screen-frame bar adjacent thereto and which are extended beyond said frame-bar, to which they are secured parallel with each other and at an angle to the frame, so that as the same is reciprocated the said plates will carry the stud o³ between the same, and thus cause the said spout to vibrate, and the vibrations thereof will carry the matter without the hopper-frame and discharge the same into the refuse-spout Q, secured at an angle to one of the side frame-pieces A and directly under the outer end of said vibrating spout.

A supplemental vibrating spout R is located directly beneath the inner end of the conveying-pan N, which receives the small refuse seed from the stream directed thereover. The spout R is also provided with the sliding supporting-pins r at one end thereof, but which work within one of the side pieces A, while the opposite end of said spout projects through the opposite side of the casing and is supported upon the swinging links r'', while the same is further provided with an operating-stud r², also engaged by a pair of angle-plates P, secured to the inner end of the lower screen-frame bar adjacent thereto and disposed at an angle opposite to that of the similar plates secured to the upper screen-frame bar, so that as the said bars are reciprocated alternately with relation to each other the said spouts vibrate simultaneously to evenly discharge their refuse. The lower spout R has its outer end directly over the upper end of the vertical conducting-spout S, secured upon the outside of the machine and opening beneath the same into the receiving box or drawer s, located beneath the machine and working transversely within the cleats s'. The good seed separated from the chaff and other foreign matter passes over the extended imperforate end m³ of the lower screen and into the air-trunk, where the same is subjected to the action of the blast of air directed through the air-trunk from the opening b in the fan-casing. The main body of the heaviest and best seed falls directly upon the inclined chute T, secured between said side pieces and passing beneath the fan-casing and to the rear of the machine, where the

seed may be collected in a suitable receptacle. According to the nature and weight of the grain not falling upon the main chute T the same is driven or blown forward under 5 the blast of air from the fan against the dividing and deflecting wings U, so disposed as to receive the grain thereagainst and cause the same to drop through and into the vertical receptacles u, located at the forward upper 10 end of the chute T and communicating with the receiving boxes or drawers u', directly therebeneath and adapted to slide under the machine in the cleats s' and u², respectively, as will be quite apparent. The said dividing- 15 wings are hinged directly above the partitions between the vertical receptacles and gradually increase in height from the innermost wing adjacent to the fan-discharge to the outermost, in order that the grain blown 20 over the top of one wing will be caught by the next succeeding wing and directed into its corresponding receptacle, while it may also be readily seen that the various wings may be moved against each other, as illustrated in dotted lines, so that the grain may 25 be directed into one or more of the vertical receptacles and the main chute, thus providing means for a separation and winnowing of the grain, according to the option of the operator. 30

A regulating board or door V is hinged upon hinges v to the top edge of the opening b in the inner side of the fan-casing and is adapted to be opened any width desired by 35 means of the operating-lever W, pivoted upon the inner side of one of the frame-pieces A, and is used to either open said gate or regulating-board or to allow the same to partially close by dropping of its own weight, according to 40 the strength of blast desired.

As previously stated, when it is desired, the belt g may be shifted from the rear feed-ing-roller to the front if it is desired to merely 45 separate the grain by subjecting the same to the direct action of the blast of air and the dividing-wings.

The construction and operation of the herein-described winnowor or fanning-mill are now thought to be apparent without further 50 description.

Having thus described my invention, what I claim, and desire to secure by Letters Patent, is—

1. In a grain-separator, the combination, 55 with the casing and the fan located therein, of a feed-hopper located above the fan and having an inclined bottom, opposite vertical grooves and slanting grooves cutting or crossing said vertical grooves, located in opposite 60 inner edges of the hopper, a corrugated feed-roller journaled in said blocks, a guard-board removably secured in said slanting grooves directly above said feed-roller, and removable regulating and cut-off gates working in said 65 vertical grooves and in front of the guard-board to secure the same in place, substantially as set forth.

2. In a grain-separator, the combination, with the casing and the fan located therein, of a double-hopper frame detachably secured 70 upon said casing and having opposite hoppers provided with centrally-meeting inclined bottoms, opposite vertical and crossing slanting grooves at the front edges of the hoppers, a corrugated feed-roller journaled at the front 75 lower edges of the hoppers, a guard-board removably secured in said slanting grooves directly above said feed-roller, removable regulating and cut-off gates working in said vertical grooves in front of the guard-boards, a 80 division cover or lid hinged at the apex or meeting point of the inclined bottoms and adapted to be thrown over either of the hoppers, reciprocating screens within said hopper-frame, and means for operating the same, 85 substantially as set forth.

3. In a grain-separator, the combination, with the casing and a fan located at one end thereof, of a detachable double-hopper frame mounted upon said casing directly over the 90 fan, opposite pairs of oscillating levers secured to opposite inner sides of said hopper-frame, upper and lower screen-frames secured pivotally to the upper and lower ends, respectively, of said levers, and means for 95 oscillating said levers, substantially as set forth.

4. In a grain-separator, the combination, with the casing and a fan located at one end thereof, of a detachable frame mounted upon 100 said casing, opposite pairs of oscillating levers secured to opposite inner sides of said frame, upper and lower screen-frames pivotally secured to the upper and lower ends, respectively, of said levers, vibrating conduct- 105 ing-spouts mounted transversely beneath the front ends of each screen-frame, and means for simultaneously oscillating said levers and vibrating said spouts, substantially as set forth. 110

5. In a grain-separator, the combination, with the casing and a fan located at one end thereof, of a double-hopper frame detachably mounted upon said casing, oscillating levers secured to inner opposite sides of said 115 frame, the rear levers having lower projecting ends, upper and lower screen-frames pivotally secured to the upper and lower ends, respectively, of said levers, curved operating-plates secured to the rear ends of the lower 120 screen-frames, a square operating-shaft journaled beneath the screen-frames and adapted to alternately strike the lower projecting ends of said levers and said curved plates, and means for simultaneously operating said shaft 125 with the fan, substantially as set forth.

6. In a grain-separator, the combination, with the casing and a fan located in one end thereof, of a double-hopper frame detachably mounted upon said casing, oscillating levers secured to inner opposite sides of said frame, the rear levers having lower projecting ends, upper and lower screen-frames secured to the upper and lower ends, respect- 130

ively, of said levers, curved operating-plates secured to the lower ends of the lower screen-frame, a square or rectangular operating-shaft journaled beneath the screen-frame, opposite 5 strike-plates secured to opposite sides at each end of said shaft and adapted to alternately strike the lower projecting ends of said levers and said curved plates, and means for simultaneously operating said shaft with the fan, 10 substantially as set forth.

7. In a grain-separator, the combination, with the casing and a fan located at one end thereof, of a detachable frame mounted upon 15 said casing, upper and lower reciprocating screen-frames working within said frame, parallel angle-plates secured to the inner ends of said screen-frames and having the ends thereof turned at an angle to the length of said frames, vibrating conducting-spouts located 20 transversely beneath the front ends of the screen-frame and provided with supporting and sliding pins secured to one end thereof and adapted to slide in the sides of said frame and casing, respectively, and with upwardly- 25 projecting studs adapted to engage between said angle-plates, swinging links supporting

the outer ends of said spouts, and means for operating said screen-frame simultaneously with the fan, substantially as set forth.

8. In a grain-separator, the combination, 30 with the casing and a fan located at one end thereof, of a series of vertical dividing-receptacles in front of said fan, a detachable double-hopper frame mounted upon said casing directly over the fan, upper and lower reciprocating screen-frames working within said hopper-frame, swinging and vibrating spouts located transversely beneath the front ends of said screen-frames and connected with and operated thereby, conducting chutes and 40 spouts under the discharging ends of each vibrating spout, a series of boxes or drawers beneath each receptacle, and means for operating said screen-frames simultaneously with the fan, substantially as set forth. 45

In testimony that I claim the foregoing as my own I have hereto affixed my signature in the presence of two witnesses.

HENRY BUSH.
